UNITED STATES PATENT OFFICE.

EMILE LAMM, OF NEW ORLEANS, LOUISIANA.

IMPROVEMENT IN SUPPLYING STEAM TO TRAVELING ENGINES.

Specification forming part of Letters Patent No. 129,969, dated July 30, 1872.

To all whom it may concern:

Be it known that I, EMILE LAMM, of the city of New Orleans, parish of Orleans, State of Louisiana, have invented a new and Improved Mode or Process of Superheating Water in the Thermo-Specific Engine, of which the following is a full and exact description:

The object of my invention is to heat above the atmospheric pressure water contained in a close vessel or reservoir on a street-car or other vehicles by means of the condensation of steam in the above-named reservoir, the steam having previously been generated under pressure in a stationary boiler. By this process I avoid discharging the water on the car, the temperature of which was lowered by the steam expended in working the engine during the trip. Thus, instead of replacing this same water in the reservoir by other and hotter water taken from the stationary boiler, I cause steam of the required temperature to rush into and condense in the reservoir until the pristine force or heat of the water is restored.

By reference to the drawing and letters thereon my invention can be easily understood.

Figure 1 is a longitudinal section.

A is the reservoir on the car. W W denote the water-line. B is an iron tube, bolted through the heads of A. This tube is closed at one end, and at the other end is provided with both a throttle-valve, C, and the one-half of a union coupling, D. This same tube is perforated inside the reservoir by a number of small holes,

the apertures of which are turned downward. The holes are placed about six inches apart through the whole interior length of the tube. Their total area should equal that of a cross-section of the tube.

The manner in which my invention operates is as follows: When the car returns from a trip the end of the tube B is connected, by means of the union coupling D, to the steam-pipe of a stationary boiler. As soon as communication becomes established, by the proper opening of throttle-valves, between the reservoir on the car and the stationary boiler, the steam from said boiler rushes into the reservoir, and by its condensation, which begins at the bottom of the water, heats the whole of it upward and in an equal degree throughout the entire length of the reservoir until this same water becomes, if desired, in equilibrium with the temperature and corresponding pressure of the stationary boiler. The car is then ready for another trip without further application of heat.

What I claim, in an apparatus for highly heating water under atmospheric pressure, is—

The combination of the perforated tube B with the reservoir A; as and for the purpose set forth and specified.

EMILE LAMM.
